UNITED STATES PATENT OFFICE.

MORTIMER PLUMER, OF BROOKLYN, NEW YORK.

DESIGN FOR A PLATE OR SIMILAR ARTICLE.

Application filed December 12, 1928. Serial No. 29,248. Term of patent 3½ years.

To all whom it may concern:

Be it known that I, MORTIMER PLUMER, a citizen of the United States, residing at Brooklyn, in the county of Kings and State of New York, have invented a new, original, and ornamental Design for Plates or Similar Articles, of which the following is a specification, reference being had to the accompanying drawing, forming part thereof.

The ornamentation as shown is continued throughout the plate.

I claim:

The ornamental design for a plate or similar article substantially as shown and described.

MORTIMER PLUMER.
